UNITED STATES PATENT OFFICE.

EDWARDS F. SCHERMERHORN, OF BROOKLYN, NEW YORK, ASSIGNOR TO THE RAIL JOINT COMPANY, OF NEW YORK, N. Y., A CORPORATION OF NEW YORK.

INSULATED RAIL JOINT.

Application filed May 4, 1925. Serial No. 27,942.

To all whom it may concern:

Be it known that I, EDWARDS F. SCHERMERHORN, a citizen of the United States, residing at Brooklyn, in the county of Kings 5 and State of New York, have invented certain new and useful Improvements in Insulated Rail Joints, of which the following is a specification.

This invention relates to an improvement 10 in insulated rail joints which is intended to permit of a material lightening of the weight of the joint bar without detracting from its inherent structural stability and strength and maintaining adequate bearings 15 for the bolt bushings.

There has been a tendency in rail joints, particularly of the insulated type, to obtain strength and stiffness largely by mere bulk of metal, and it is the purpose of the 20 present invention to provide a new distribution of metal in a joint bar intended for use in the fabrication of an insulated rail joint whereby such bar may be materially lightened in weight and which at the same time 25 will have sufficient structural strength and resiliency to resist the usual loading and deflection forces. Also the invention provides a construction wherein the length of the bolt holes will not be materially diminished, 30 thus maintaining adequate bearing for the bolt insulating bushings to resist extreme compressive forces which are exerted theoretically in a line coinciding with the central line of the bolt holes.

35 Though susceptible of structural modification without departing from the purposes of the invention, the same consists in the novel bar construction herein described, illustrated and claimed, and a preferred and practical embodiment is shown in the accompanying drawings in which

Figure 1 is a half view of an insulated rail joint showing the rail joint in end elevation and the rail in section.

45 Figure 2 is a half sectional view of an insulated rail joint embodying the present invention.

50 Figure 3 is an inside elevation of a joint bar deformed according to the plan of metal distribution contemplated by the present invention.

55 Referring to the exemplification of the invention shown in the drawings the numeral 1 designates the rail with which is as-

sociated the joint bar 2 having an outer vertical bolting face 3 against which clamps the insulated washer-unit 4 carried by the joint bolt 5 extending through the bolt hole 6 in the joint bar.

55 In insulated joint structures of the type shown a bolt bearing bushing 7 receives the joint bolt and is fitted within the bolt hole 6 of the joint bar and it is quite essential to provide an adequate bearing for this insulating bushing to enable it to better resist destruction from extreme compressive forces.

60 This is taken care of in the present invention by providing a maximum thickness of the bar along the longitudinal line of the bolt holes, namely by deforming the bar, at 65 its inner side, in such a manner as to provide the bar with an inside longitudinally extending bolt-bushing bearing-rib 8. This

70 bearing-rib extends longitudinally of the bar the full length thereof and is disposed in the longitudinal plane of the bolt hole locations, and therefore lies in an intermediate position between the head and foot of the bar. The said rib 8 is of such a projection from the inside of the joint bar as to provide an extended bearing for the insulating 75

bolt-bushing 7 so as to provide the adequate bearing support for the bolt-bushing for the reasons above explained. In connection 80 with that feature of construction, namely, the inwardly projecting bolt bearing rib 8 which is pierced by the bolt holes, the plan of metal distribution, according to the present invention, provides for channeling or

85 grooving the inner side of the joint bar both above and below the rib 8 as indicated by the reference numerals 9 and 10 respectively, the said channeling 9 and 10 representing substantial bodies of metal removed from the inner side of the bar above and below 90

95 the rib 8. The effect of such channeling 9 and 10 is to provide subnormally thinned portions for the bar web longitudinally throughout the bar from end to end thereof with the result of greatly lightening the 100

105 bar but still leaving it with the requisite structural strength to properly resist the loading and deflection forces to which the same is subjected in track.

In an insulated joint of the type described the customary head insulation 11 is used between the head of the bar and the head of the rail, and suitable base insula-

tion 12 is incorporated in the joint between the rail base flange and the foot and base flanges of the bar.

From the foregoing it is thought that the 5 features of construction herein claimed as an improvement in an insulated rail joint will be readily understood without further description.

I claim:—

10 1. An insulated rail joint including a joint bar fitting within the fishing spaces of the rail and deformed at its inner side to provide subnormally thin portions and also an inwardly projecting bolt-bushing bearing-rib lying in the longitudinal plane of the bolt holes and pierced thereby, and insulation interposed between the joint bar and the rail.

20 2. An insulated rail joint including a joint bar fitting within the fishing spaces of the rail and deformed at its inner side to provide an inwardly projecting and longitudinally extending bolt-bushing bearing-

rib disposed in the horizontal longitudinal plane of the bolt holes and pierced thereby, 25 said bar being also provided at its inner side with a longitudinal channel or recess forming a subnormally thinned bar portion, and insulation interposed between the joint bar and the rail.

30 3. An insulated rail joint including a joint bar fitting within the fishing spaces of the rail and deformed at its inner side to provide an inwardly projecting and longitudinally extending bolt-bushing bearing-rib disposed in the horizontal longitudinal plane of the bolt holes and pierced thereby, 35 said bar being also provided above and below said rib with grooves or channels forming subnormally thinned bar web portions, and insulation interposed between the joint bar and the rail.

40 In testimony whereof I hereunto affix my signature.

EDWARDS F. SCHERMERHORN.
